COMPRESSOR GOVERNOR CONSTRUCTION

Clyde C. Farmer, Pittsburgh, Pa., assignor to The Westinghouse Air Brake Company, Wilmerding, Pa., a corporation of Pennsylvania

Application August 2, 1933, Serial No. 683,337

4 Claims. (Cl. 137—153)

This invention relates to pressure regulating devices and more particularly to governors for controlling the admission of steam to a fluid compressor.

5 In my prior Patent No. 1,921,609, issued August 8, 1933, a governor construction for controlling the operation of a steam compressor driven by super-heated steam is disclosed which includes a barrier plate clamped between the piston bushing and the piston cylinder section for radiating heat which would otherwise be transmitted from the steam valve portion to the non-pressure chamber below the piston. The exterior surface of the barrier plate is maintained fairly cool by 10 atmospheric air currents circulating freely over it and the non-pressure chamber side of the plate is in communication with the atmosphere through openings in the piston bushing which communicate with an annular space surrounding the bushing, said space being open to the atmosphere.

20 The principal object of my invention is to provide a steam compressor governor of the above type having improved means for permitting a flow of air from the annular space surrounding the piston bushing to the non-pressure chamber below the piston.

25 Another object of my invention is to provide a barrier plate having improved means for holding said plate securely in position between the piston bushing and the piston cylinder section regardless of variations in the manufacture of these parts, so that the plate will not rattle due to vibration.

30 Other objects and advantages will appear in the following more detailed description of the invention.

In the accompanying drawing; Fig. 1 is a sectional view taken vertically through a steam compressor governor embodying my invention; and Fig. 2 is a plan view of the barrier plate embodied in the compressor governor.

35 It should be understood that whereas the steam compressor governor shown in the drawing is of the so called single top type, my invention may also be applied to a steam compressor governor of the double top type.

40 As shown in Fig. 1, the governor may comprise a steam valve body 1, a cylinder section 2, and a cylinder head 3. The cylinder section 2 is provided with a cylindrical boss 4 which fits into an annular recess formed in the body 1, and the section 2 is clamped to the body 1 by means of bolts 5 (two of which are shown).

45 The body 1 is provided with a partition wall 6

which separates the steam inlet chamber 7 from the outlet chamber 8 and is provided with a valve seat for a steam valve 9. The steam valve is carried by a stem 10 which extends upwardly through a bore in a guide bushing 11. The bushing 11 is 5 provided with a circular flange 12 which extends into the recess formed to receive the boss 4 and rests upon a gasket 13, the flange 12 being clamped in place by the bolts 5 when the section 2 is secured to the body 1.

10 Loosely carried within an axial bore in the stem 10 of the steam valve 9 is a stem 14, the upper end of which is pressed into an axial bore in a piston 15 and in an axially disposed boss 16 on the upper side of the piston 15, with a 15 collar 17 on said stem engaging the lower side of said piston, the stem 14 being preferably peened over at the upper end of the boss 16.

The boss 16 slidably engages a boss 32 mounted in a bore in the section 3 for guiding the movement of the piston 15.

20 The piston 15 works in a slip bushing 18 having an annular flange 19. The flange 19 extends into an annular recess formed at the upper face of the section 2 and is clamped in place when the head 3 is secured to the section 2 by means of bolts (not shown), a gasket 20 being interposed between the clamping faces of the section 2 and the head 3. The bushing 18, for a portion of its length from the bottom, is spaced away 25 from the inner wall of the section 2, so that an annular chamber 21 is formed between said bushing and said wall.

25 Interposed between the lower end of the bushing 18 and an inwardly extending annular ledge 35 22 of the section 2 is a barrier plate 23 which is preferably pressed from a section of sheet metal and is preferably of cup shape, having at one end an outwardly extending horizontally disposed annular supporting flange 24 having portions 30 40 45 50 55 25 which are adapted to rest on said annular ledge 22.

The flange 24 is provided with spaced resilient fingers or lugs 26 which project beyond the upper face of the flange 24 and which are adapted 45 to be engaged by the lower face 27 of the bushing 18. These lugs are preferably resilient and are integral with the flange 24. Each lug may be formed by slitting the flange and bending the slit portion upwardly. In the present embodiment of the invention, each lug is formed by slitting the flange 24 inwardly from its periphery in two places and bending the metal between the slits upwardly, but it will be understood that 55

these lugs may be formed in any other desired manner.

When the bushing 18 is clamped in place, as aforementioned, the lower face 27 of said bushing engages and presses down on the upper face of the resilient fingers or lugs 26 with sufficient pressure to maintain the portions 25 of the flange 24 seated on the ledge 22. It will be seen that due to the resiliency of the lugs, the flange 24 will be held in tight engagement with the ledge 22 regardless of variations in manufacture which may affect the distance between the lower face 27 of the bushing 18 and the ledge 22.

Spaces 28 are formed between the lower face 27 of the bushing 18 and the portions 25 of the flange 24, so that communication is open through said spaces from the annular chamber 21 to the chamber 29 below the piston 15 and within the barrier plate 23, for a purpose which will appear hereinafter.

The lower portion of the barrier plate 23 is provided with a central opening into which extends an annular boss 30 of the section 2. An opening 31 is provided in the barrier plate, affording communication from chamber 29 to the atmosphere. The section 2 is provided with openings 32 to permit free circulation of air through the space surrounding the plate 23.

A passage 34 in the cylinder head 3, communicating with the chamber 35 above the piston 15 and containing a choke plug 36, registers with a passage 33 in the cylinder section 2 leading to the annular chamber 21, for permitting a controlled flow of fluid under pressure from chamber 35 to the chamber 21, as will be understood from the description hereinafter.

The governor top comprises a spring box 37 having screw-threaded engagement in the head 3. A valve seat bushing 38, provided with an annular flange 39 is mounted in a bore in a partition wall 59 which separates chamber 58 from the piston chamber 35, and a flexible diaphragm 40 is mounted to engage the flange. On the opposite side of the diaphragm is a ring 41 which engages the lower end of the spring box 37, so that when the spring box is screwed into place the diaphragm 40 and the seat bushing 38 are clamped in place.

Mounted in the valve seat bushing is a valve 42 adapted to engage a seat provided in said bushing and the valve 42 is provided with a rectangular guide head 43, the rounded corners of which engage the cylindrical guide wall in the bushing 38, and when these corners are in such engagement, there will be spaces between the straight sides of the head and the cylindrical guide wall of the bushing through which fluid under pressure supplied through passages 57 in the bushing from the chamber 58 is supplied to the chamber at one side of the flexible diaphragm 40.

Mounted in a chamber 55 provided in the bushing 38 is a coil spring 44 having one end in engagement with a spring plate 45. The central portion of the spring plate is provided with a rounded depression adapted to receive the rounded end of a stem 46 carried by the valve 38.

The lower end of the spring 44 is engaged by a spring plate 47 which is held in place by a spring ring 48 which is mounted in an annular groove formed in the bushing 38.

The spring chamber 55 is in communication with the chamber 35 above the piston 15 through the openings 56 in the bushing wall.

Mounted in the spring box 37 is an adjustable

coil spring 49, one end of which wears on a follower plate 50 engaging the flexible diaphragm 40.

The upper end of the spring engages a spring plate 51 having a rounded depression for the reception of the rounded end of an adjusting screw 52 which is screw-threaded into the upper wall of the spring box 37, with a head 53. A lock nut 54 is mounted on the screw to provide for clamping the screw in its adjusted position.

The bushing 11 is provided with a chamber 60 which opens into a chamber 61 and this latter chamber is open to the atmosphere through a passage 62. Possible leakage of steam from the chamber 8, around the stem 10, to the chamber 15 60 will be free to flow to the atmosphere by way of chamber 61 and atmospheric passage 62. By this construction, the chamber 29, defined by the barrier plate 23, bushing 18 and piston 15, will be substantially free from leaking steam. If steam should leak into the chamber 29, it will be free to flow to the atmosphere by way of the opening 31 in the barrier plate 23.

The governor top operates in the usual well known manner to control the operation of the valve 38 which, in turn, controls the operation of the steam valve 9. When the valve 38 is unseated, fluid under pressure is supplied to the piston chamber 35, causing the piston 15 to be moved downwardly so as to partially or wholly close the valve 9. Fluid under pressure thus supplied to the chamber 35 flows to the atmosphere by way of the choke plug 36, passages 34 and 33, chamber 21, the spaces 28 between the lower face 27 of the piston bushing and the flange 24 of the barrier plate 23, chamber 29, and thence through the opening 31 in the barrier plate. This flow of fluid under pressure cools the bushing 18, the cylinder section 2 and chamber 29 below the piston 15.

When the valve 38 is seated, fluid under pressure in chamber 35 above the piston 15 is vented to the atmosphere by way of the choke plug 36, passages 34 and 33, chamber 21, spaces 28, chamber 29 and the opening 31, thereby permitting steam in chamber 7 acting on the steam valve 9 to open said valve.

The outer surface of the barrier plate 23 is cooled by currents of atmospheric air which pass through the openings 32 in the cylinder section 2.

Thus, the barrier plate, being cooled in the above described manner, prevents any considerable heat from being transmitted to the chamber 29 below the piston 15, which would interfere with the lubrication and proper operation of the piston 15.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. In a steam pump governor, the combination with a cylinder casing, a bushing mounted in said casing adapted to receive a piston and having one end spaced from said casing, and a barrier plate mounted in said casing and having a flange disposed in the space between the end of the bushing and the casing, and resilient fingers formed in said flange and engaged by the end of the bushing to yieldingly maintain said plate in position with a substantial portion thereof in spaced relation to the end of said bushing.

2. In a steam pump governor, the combination with a casing, a bushing mounted in said casing and having one end spaced from said casing, a piston mounted in said bushing, a cap for securing said bushing to said casing, said cap, bushing and piston defining a pressure chamber, and means providing an always open communication between said pressure chamber and the space between the end of the bushing and the casing, 5
10 of a barrier plate mounted in said casing and having a flange disposed in a portion of the space between the end of the bushing and the casing, said bushing, piston and barrier plate defining a non-pressure chamber communicating with said space, and resilient lugs formed in said flange and engaged by the end of said bushing to yieldingly maintain said plate in position.
15 3. In a steam pump governor, the combination with a casing having a shoulder, a bushing mounted in said casing and having one end spaced from said shoulder, a piston mounted in said bushing, a cap for securing said bushing to said casing, said cap, bushing and piston defining a pressure chamber, of a barrier plate having a flange resting 20
25 on said shoulder, said bushing, piston and bar-

rier plate defining a non-pressure chamber, said barrier plate having resilient fingers bent in said flange and engaged by the end of the bushing to yieldingly maintain said plate in spaced relation between the bushing and the flange to provide 5
10 passages for effecting communication between said pressure chamber and said non-pressure chamber.

4. In a steam pump governor, the combination with a casing having a shoulder, a bushing mounted in said casing and having one end spaced from said shoulder, a piston mounted in said bushing, and a cap for securing said bushing to said casing, said cap, bushing and piston defining a pressure chamber, of a barrier plate having a flange 15 resting on said shoulder, said bushing, piston and barrier plate defining a non-pressure chamber, and resilient lugs formed in said flange and engaged by said bushing to yieldingly maintain said plate in position, the spaces between the lugs 20
25 forming vent passages from the pressure chamber to the non-pressure chamber through the space between the end of the bushing and the portions of the flange between said lugs.
